US0D1094517S

(12) **United States Design Patent** (10) **Patent No.:** **US D1,094,517 S**
(45) **Date of Patent:** **** Sep. 23, 2025**

(54) **CAMERA**

(71) Applicant: **ARASHI VISION INC.**, Shenzhen (CN)

(72) Inventors: **Limin Ma**, Guangdong (CN); **Lingwu Huang**, Guangdong (CN); **Fei Gao**, Guangdong (CN); **Jingkang Liu**, Guangdong (CN)

(73) Assignee: **ARASHI VISION INC.**, Shenzhen (CN)

(**) Term: **15 Years**

(21) Appl. No.: **35/522,776**

(22) Filed: **Sep. 30, 2024**

(80) **Hague Agreement Data**

Int. Filing Date: **Sep. 30, 2024**

Int. Reg. No.: **DM/241080**

Int. Reg. Date: **Sep. 30, 2024**

Int. Reg. Pub. Date: **Oct. 25, 2024**

(51) **LOC (15) Cl.** **16-01**

(52) **U.S. Cl.**

USPC **D16/218**; D16/202

(58) **Field of Classification Search**

USPC D16/200, 202–208, 218, 219

CPC G03B 17/02; G03B 19/04; G03B 17/56; G03B 17/04; G03B 15/03; H04N 23/50; H04N 23/51; H04N 23/54; H04N 23/55; H04N 23/62; H04N 23/63; H04N 7/181; H04N 7/183; H04N 7/18

(57) **CLAIM**

The ornamental design for a camera as shown and described.

DESCRIPTION

1. Camera
2. Camera
- 1.1 : Front
- 1.2 : Back
- 1.3 : Left
- 1.4 : Right
- 1.5 : Top
- 1.6 : Bottom
- 1.7 : Perspective
- 2.1 : Front
- 2.2 : Back
- 2.3 : Left
- 2.4 : Right
- 2.5 : Top
- 2.6 : Bottom
- 2.7 : Perspective

The broken lines shown in the drawings depict environmental subject matter and form no part of the claimed design; The characteristic features of the design lie in the shape.

1 Claim, 14 Drawing Sheets
